UNITED STATES PATENT OFFICE.

FRANK T. FARMER, OF PHOENIX, ARIZONA, ASSIGNOR OF ONE-HALF TO PAUL N. FARMER, OF PHOENIX, ARIZONA.

CARBURETOR AUXILIARY.

Application filed October 26, 1920. Serial No. 419,653.

To all whom it may concern:

Be it known that I, FRANK T. FARMER, a citizen of the United States, residing at Phoenix, in the county of Maricopa and 5 State of Arizona, have invented certain new and useful Improvements in Carburetor Auxiliaries, of which the follow is a specification.

This invention relates to a carburetor auxiliary for internal combustion engines of the type adapted to introduce into and mix an additional supply of air with the combustible mixture from the carburetor, whereby more perfect combustion is obtained and 15 correspondingly increased power and efficiency imparted to the engine.

More specifically, the device comprises a chambered body portion having a constricted entrance opening and an exit opening for 20 the combustible gas from the carburetor; an inclined baffle plate in said chambered portion against which the incoming gas impinges; and a valve-controlled air inlet pipe projecting into the chamber and serving to 25 direct a stream of air against the face of the baffle plate during operation of the motor. The shape of the baffle plate and its location and position with reference to the other parts of the device, more particularly, the 30 air inlet pipe and the gas inlet opening, all contribute materially to the obtaining of a thorough mixture of the air and gas, and ultimately the greatest amount of power from a given quantity of gasolene.

35 The construction of the device is such as to enable its ready connection to the engine between the carburetor and the intake manifold without the necessity of change of, or alteration in, known parts, use being made 40 of the usual connecting bolts to secure the auxiliary in place.

A practical embodiment of the invention is illustrated in the accompanying drawings, wherein like numerals indicate the same 45 parts throughout the several views, and wherein:

Fig. 1 is a vertical section taken on line 1—1 of Fig. 2, the auxiliary being shown in place between the carburetor and the end 50 flange of the engine manifold;

Fig. 2, a rear elevation of the device removed from the engine;

Fig. 3, a front elevation, the lower portion of the air inlet pipe being broken away and 55 the valve omitted;

Fig. 4, a similar front elevation with the cover plate removed;

Fig. 5, a horizontal section taken on line 5—5 of Fig. 4;

Fig. 6, a front perspective of the device 60 with the cover plate removed in order to show clearly the arrangement of the baffle plate with reference to the air inlet pipe; and

Fig. 7, a front perspective of the baffle 65 plate removed from the device.

In the drawings, Fig. 1, A represents a portion of a carburetor, and B a portion of the intake manifold of an engine. The carburetor auxiliary is shown secured in operative position between these members, the adjacent portions of which are partially broken away to show the relative positions of the parts.

The auxiliary proper, which may be made 75 of any suitable metal, comprises a main body portion 1 provided with an annular central mixing chamber 2, having at one end a central restricted outlet 3 through which the completed mixture of gas and added air pass 80 to the manifold B. Suitably mounted in the lower part of the body portion 1 of the device is an air inlet pipe 4, the upper end of which projects into the bottom of chamber 2, while the lower end leads to the open air. 85

Disposed diagonally across chamber 2 in front of outlet 3 and above inlet pipe 4, is a baffle plate 5 provided with forwardly projecting ears 6, 7, the lower edges of the inclined plate and said ears extending below 90 the upper end of inlet pipe 4. Any suitable means may be provided for securing baffle 5 in proper position. As shown in the drawings, this is accomplished by providing a shoulder 8 on body portion 1 against which 95 projection 9 and the outer extremities 10, 11 of ears 6, 7 of the baffle plate are secured by solder, thereby rigidly securing the baffle in place. A cover plate 12 having a central restricted opening 13, serves to form the other 100 wall of chamber 2, and is also secured to body 1 by solder, or other suitable means.

The upper end of air-inlet pipe 4, as stated, projects into chamber 2 above the lower edge of baffle 5, but below inlet opening 13 in cover plate 12. Suitably secured to the lower end of air inlet pipe 4 is a vertically disposed plate 14 having an opening 15 registering with the opening in the end of the pipe to permit the entrance of air. Piv- 110

totally secured to the upper portion of plate 14, by means of bolt 16 and nuts 17, is a valve member 18 adapted to control the admission of air to pipe 4. Spring 19 serves 5 to firmly maintain member 18 against the face of plate 14. Provided in the lower end of valve 18 is an opening 20 having a contracted portion 21, whereby entrance of the desired amount of air into the auxiliary may 10 be accurately controlled. A goose neck 22, rigidly attached to the upper end of valve member 18 and extending around manifold B, is adapted to be connected at its outer end with a suitable push and pull member 15 23 extending from a convenient point of operation, as beside the steering post in the case of an automobile engine. Slots 24, 25 in the upper end of pipe 4 have a purpose which will appear later.

20 The device being in place as shown in Fig. 1, and the engine started resulting in suction through manifold B as indicated by the arrows in Fig. 1, the operation is as follows:

The suction in manifold B draws the 25 usual combustible mixture of gas and air from carburetor A, through opening 13 of cover plate 12 into chamber 2 of the auxiliary device, at the same time causing a quantity of added air, depending on the position 30 of valve member 18, to be injected into the chamber. The combustible mixture passing through inlet opening 13 and coming into contact with baffle 5, is by reason of the inclined position of the latter, deflected downwardly 35 toward the upper end of inlet pipe 4 and the jet of air being emitted therefrom, thus accomplishing a thorough intermingling of the mixture and the added air. Ears 6, 7 on baffle 5 further serve to concentrate 40 the mixture about the end of the air inlet pipe 4. It is to be noted that opening 13 in cover plate 12 is located centrally with relation to baffle plate 5 and is of a size sufficiently small to cause the jet of combustible 45 mixture to strike baffle 5 within the angles produced by ears 6, 7, and against the central inclined portion thereof so that the entire stream of mixture is thrown downwardly.

50 An important feature of the device is the angular openings or passageways 26, 27 formed at either side of chamber 2 by the sides of baffle 5, cover plate 12 and the sides of chamber 2, and openings 28, 29 formed by the lower edge of baffle 5, air inlet pipe 4 and the lower wall of chamber 2. The combined combustible mixture and added air formed on the forward side of baffle 5 is sucked through these openings, the several 55 currents, thin at the acute angles of the openings and thick at the obtuse angles, rushing into the portion of chamber 2 at the rear side of baffle 5, and finally coming together 60 in a single stream as the completed mixture 65 passes through opening 3 into manifold B

on its way to the engine. Slots 24, 25, in the upper end of pipe 4 permit a sheet of air to pass into the current of combustible mixture flowing under baffle 5, thus insuring thorough mixing of the added air with all 70 the combustible gas entering through inlet opening 13.

While the construction shown illustrates a practical embodiment of the invention, it is not intended that the same shall be confined to these means except as limited by the appended claims.

I claim:

1. The combination in a device of the character described, of a mixing chamber 80 having a gas inlet opening and a gas outlet opening; and an inclined baffle plate located in said chamber intermediate said openings, the mixing chamber being provided with an air inlet for discharging air transversely of 85 said gas inlet opening and against the face of said baffle plate facing said gas inlet opening.

2. The combination in a device of the character described, of a mixing chamber 90 having a restricted gas inlet opening and a restricted gas outlet opening; and an inclined baffle plate located in said chamber between said openings, the chamber being provided with an air inlet for discharging 95 air transversely of said gas inlet opening and against the face of said baffle plate facing said gas inlet opening.

3. The combination in a device of the character described, of a mixing chamber 100 having a central restricted gas inlet opening and a gas outlet opening; and an inclined baffle plate located in said chamber intermediate said openings and extending completely across said inlet opening, said 10 chamber being provided with an air inlet for discharging air transversely of said gas inlet opening and against the face of said baffle plate facing said gas inlet opening.

4. The combination in a device of the character described, of a mixing chamber having a gas inlet and a gas outlet; and an inclined baffle plate having ears projecting forwardly from the lower portion thereof, 11 said chamber also being provided with an auxiliary air inlet opening in line with said baffle plate.

5. The combination in a device of the character described, of a mixing chamber 12 having a gas inlet, a gas outlet and an auxiliary air inlet intermediate said gas inlet and said gas outlet; and a baffle plate having an inclined body portion provided with forwardly projecting ears, said inclined 13 body portion overlying said air inlet.

6. In a device of the character described, the combination of a mixing chamber having an air inlet at its bottom and a gas inlet at its forward end; and an inclined baffle 1

- plate located in said chamber and provided with forwardly projecting ears, said gas inlet opening being of a diameter not greater than the width of the inclined portion 5 of said baffle plate.
7. In a device of the character described, the combination of, a mixing chamber having a gas inlet and an air inlet; and a baffle plate located in said chamber, said baffle 10 plate comprising an inclined body portion extending across said gas inlet and above the air inlet, and forwardly projecting ears extending from the sides of said body portion about the air inlet.
- 15 8. In a device of the character described, the combination of a mixing chamber having a gas inlet and a gas outlet; an inclined baffle plate located in said chamber intermediate said inlet and said outlet; 20 and an air pipe for discharging air transversely of said gas inlet and against the face of said baffle plate facing said gas inlet, said pipe extending within said chamber to a point above the lower edge of the 25 baffle plate.
9. In a device of the character described, the combination of a mixing chamber having an inlet and an outlet; an inclined baffle plate located in said chamber intermediate 30 said inlet and said outlet; and an air pipe extending within said chamber to a point above the lower edge of said baffle plate, said pipe being slotted at its inner end.
10. In a device of the character described, 35 the combination of a mixing chamber having an inlet and an outlet; an inclined baffle plate located in said chamber intermediate said inlet and said outlet; and an air pipe extending within said chamber to a point
- above the lower edge of said baffle plate 40 and below said inlet.
11. In a device of the character described, the combination of a mixing chamber having a gas inlet and a gas outlet; and a baffle plate located in said chamber intermediate 45 said gas inlet and said gas outlet, said baffle plate comprising an approximately hexagonal body portion and a pair of forwardly projecting ears extending from the lower sides thereof about an auxiliary air inlet 50 provided in said chamber.
12. In a device of the character described, the combination of a cylindrical mixing chamber; an air pipe extending partially within said chamber, and a baffle plate 55 located within said chamber and overlying said air pipe, said baffle plate comprising an approximately hexagonal inclined body portion, secured at its upper side to the wall of said chamber, and forwardly projecting 60 ears extending from the lower sides of said body portion and attached to the wall of said chamber, said chamber being provided with a gas inlet, wholly in line with the inclined body portion of said baffle plate. 65
13. In a device of the character described, the combination of a cylindrical mixing chamber having a gas inlet, a gas outlet and an air inlet; and an angular baffle located within said chamber intermediate 70 said air inlet and said gas outlet, said baffle being secured at intervals on its periphery to the walls of said chamber to form restricted openings for the passage of the gas and air. 75

In testimony whereof I have signed my name to this specification.

FRANK T. FARMER.
